CLAIM

I claim the ornamental design for a chip extractor, as shown and described.

DESCRIPTION

FIG. 1 is a plan view of a chip extractor showing my new design;

FIG. 2 is a top end view thereof;

FIG. 3 is a right side elevational view thereof;

FIG. 4 is a left side elevational view thereof;

FIG. 5 is a front side elevational view thereof; and,

FIG. 6 is a rear elevational view thereof.
